STEAM HEATING

Minor W. Stout, Webster Groves, Mo.

Application January 20, 1936, Serial No. 59,856

4 Claims. (Cl. 237—67)

This invention relates to improvements in steam heating, and more particularly to improved steam apparatus for certain industrial heating purposes.

5 It is among the general objects of this invention to improve the heat balance in industrial heating installations, such for example as laundries, and to economize, through an increase in efficiency of the system, in both pounds of 10 fuel required and gallonage of water heretofore necessary in systems of the broad category or type referred to.

Yet another object of the invention is attained in improved means for controlling the condensate 15 flow from steam-consuming units either of different type, or relatively so located as to require different discharge or outlet pressures for comparable steam flow and evacuation of condensate, this object being presently expressed in reference 20 to the installation of such units in a system characterized by a common steam supply and common condensate return provisions. The practice characterizing the present invention in this respect, enables a substantial variation in pressure drop 25 through the units, even though the units be connected in a closed system and supplied from a common pressure source, such as a boiler.

The present application constitutes certain improvements over and modifications of the subjects disclosed and claimed in U. S. Patent No. 1,984,290 issued December 11, 1934 to this applicant, and the foregoing and numerous other objects will more fully appear from the following detailed description of the apparatus preferably 30 utilized and illustrated by the accompanying drawings, in which:

Fig. 1 is a schematic layout of a steam system in which are incorporated the principles of the present invention; Fig. 2 is a vertical sectional 40 elevation through the condensate receiver or reservoir of Fig. 1, as viewed along line 2—2 thereof; Fig. 3 is a side elevation, partly in section, of a condensate pumping unit of a type preferred for use in the practice of the present 45 invention; Fig. 4 is a schematic elevation in the nature of a piping diagram of certain parts of a steam system employing steam-consuming units of dissimilar type, and illustrating a provision for compensation of condensate removal from 50 and steam delivery to the different units, and Fig. 5 is a vertical longitudinal sectional elevation of one of the steam-consuming units shown by Fig. 4.

Referring now by characters of reference to 55 the drawings, there is indicated generally at 2,

a boiler, which for purposes of the present description may be regarded broadly as a steam generating unit of any desirable or suitable type. The boiler 2 is provided with a dome 3 and a steam supply line 4, to which is connected one 5 or more branches 5 for the supply of steam-consuming units, which in a laundry installation may be typified by a flat work ironer 6 and a press 7. The ironer 6 is provided with a condensate return line 8, and the press with a corresponding return line 9, the several return pipes being directed to a condensate receiver or reservoir 10.

Directed from the bottom of the condensate reservoir 10, is a return pipe 11, leading preferably to the inlet fitting of a pump designated generally at 12, the pump being preferably of a rotary type characterized by an open impeller, such as a centrifugal pump, as shown, or a so-called peripheral pump. It is a further 20 preference to provide a pump of a type in which the impeller clearance may be adjusted, all as hereinafter more fully described.

The pump 12 is provided, by preference, with a horizontally disposed discharge port 13, the discharge being connected into a boiler return pipe 14 through which the condensate is delivered or returned, past a check valve 15 which is, by preference, of swinging gate, rather than of plug type, and thence is impelled through a continuation of the line 14 to the boiler 2. The provision of a horizontal discharge line adjacent the pump, tends to avoid steam pockets which might otherwise result at the top or on the discharge side of the pump.

As a convenient and preferred expedient for adding makeup water to the system, a booster pump 16 is utilized, the inlet side of this pump being connected to a suitable source of supply indicated at 17, and which may consist, for example, of the usual municipal supply main. In case the supply pressure satisfactorily exceeds the working pressures, the booster pump may be dispensed with. Assuming the pump to be utilized, as in most installations, its discharge is 45 directed as through a pipe 18 through a suitable check valve 19, and thence through means hereinafter described, into the condensate reservoir 10. In certain installations, and as may be desired, a float switch 20, or its equivalent, serves 50 with the pump 16, when motor driven, to start the booster pump as the water level in the boiler 2 permits a float 21 to actuate the switch 20. The switch is connected as through a control line 22 to the motor (not shown) for the booster 55

pump. Obviously, the booster pump may be selectively controlled by manual means, either alone or adjunctively to the automatic control described.

5 One of the improvements characterizing the present practice and apparatus, consists in the provision for introducing the makeup water to the system, as from the pump 16 and line 18, in the form of a divided stream, and entirely 10 within a steam zone of the return portions of the system. This desirability is exemplified in the present example by a nozzle 25 (Figs. 1 and 2). An economical and effective manner of producing such a nozzle is to utilize a section of pipe 15 on the terminus of the line 18, internally of the receiving tank 10. The nozzle 25 may be disposed vertically, or at an angle to the vertical, as shown by Fig. 1. It is preferably characterized by a plurality of horizontal apertures, conveniently formed as saw-cuts 26. The lower end 21 of the nozzle 25 being closed, the slotted openings 26 serve to deliver the makeup water or such water as may be required for cooling and condensing effects, in the form of a plurality of flat 20 streams which are by preference directioned 25 axially of the container 10.

As a convenient means for supporting or mounting the receiver 10, it is my preference to utilize a pair or more of spaced saddle elements 30 30. These may conveniently consist of metal members carried by a base, or mounted directly on the supporting floor. Where base mounted, the same substructure is conveniently utilized to support the motor and pump assembly of Fig. 3, 35 hereinafter described.

The air-venting provision in the example of the disclosure, consists of a short riser pipe 31 at the top of the receiver, to which is connected, as through an L fitting, a branched pipe 32, one 40 of the branches of which may, if desired, be provided with a manually operable valve such as a pet cock 33, and the other branch of which is characterized by at least a moderate slope, as appears in Fig. 2. This sloped section of conduit 45 is provided at its outer end with an L 34, serving to carry a thermal-responsive air-relief valve 35.

Referring now to the type of pumping unit preferred for use as a part of the present system and by further preference of a design adapted 50 for continuous operation when the system is in use, there is illustrated by Fig. 3 a direct-connected assembly embodying an electric motor 40, carried by a base 41 and connected as through a coupling 42 to the pump. This coupling is 55 preferably of a type, for reasons which will appear, to permit a certain limited axial movement of the pump shaft without disturbing the axial setting of the motor shaft. By preference, the unit is characterized by bearings or journaling 60 provisions entirely intermediate the motor and the pump, this assembly being indicated generally at 43 and including an axially adjustable thrust bearing 44 of anti-friction or ball type, adjacent which is an adjusting nut 45. The 65 pump housing 46 serves operatively to enclose a pump impeller or runner 47. In the example of the disclosure this is of half-open or open-side type, and the operating clearance 48 of the runner is obviously adjustable at any time through 70 adjustment of the nut 45. The inlet 50 of the pump is shown as applied through the line 11 from the condensate receiver 10. It will appear as obvious from the showing of Fig. 3 and the provisions for adjustment, that the clearance 48 75 provides a continuous steam by-pass around the

impeller 47 so that at all times the steam pressure in the lines 11 and 14 is practically the same.

Referring now to the arrangement of Figs. 4 and 5 of the drawings, there are illustrated, by way of example, a plurality of presses 55, each provided with its individual return line 56 and steam supply branches 57. The condensate return lines 56 communicate with a common conduit or header 58, shown as discharging into a vertical or riser pipe 60 which is connected through a U-shaped or loop portion indicated generally at 61, and thence to the lower portion of a condensate receiver 62. The latter element may be of the same construction and arrangement as the receiver 10 of Fig. 1, and is provided with an air-vent pipe consisting of portions 63 and 64 including a heavy duty air-relief vent or valve 65, which may be of the same type as the one illustrated at 35 in Fig. 1. A fresh water supply pipe is shown at 70, and the receiver 62 is provided internally with a spray nozzle 71 which may be and is preferably of the same type as that shown at 25. The receiver 62 is preferably kept substantially evacuated of liquid, through a condensate return line 72 connected 20 to the inlet of a pump 73 which may be and is preferably of the type illustrated by Fig. 3.

The arrangement of Fig. 4 shows an improved provision for connecting steam-consuming units requiring different steam pressure drops there- 30 through in order to effect comparable rates of steam flow to the units, and to effect an equivalent disposal of condensate therefrom. This condition often prevails where the consuming units are of different types as illustrated by Fig. 35 4, wherein 75 represents a steam-heated roll, such as an ironer, paper mill roll or many of the other elements of this general type utilized for industrial heating and processing. The members 75, since each is mounted for rotation about its 40 longitudinal axis, are provided with an axial steam supply line or inlet 76, and an outlet or condensate return line 77. Due to the rotation of the member 75, the return line is curved down- 45 wardly so that its inlet is always at the bottom 45 of the chamber within the roll, this internal, downturned portion being indicated at 78. The line 77—78 is preferably provided with a pet cock 80 which may be utilized for inspection purposes and for initiating the siphon effect through pipe 50 78, after a shutdown period. The line 77 is directed from this point into a T fitting 81. As a convenient and economical means of making up this fitting, one or the upper end of the T is provided with a threaded plug 82 which serves 55 threadedly to carry a makeup water inlet pipe 83, which projects downwardly substantially beyond the end of pipe 77, the latter projecting through a threaded plug 84 in the side of the fitting. Pipes 83 may be connected to the water supply 60 as through a booster pump (not shown) and may be provided with valves (not shown). It results from the arrangement illustrated by Fig. 5 that water admitted through the pipe 83, due to its projection beyond the pipe 77 and the 65 clearance about the element 83 where it projects into the condensate drain line 85, causes this element to function as an ejector, tending to evacuate the condensate from the roll 75. This action of the assembly results in a reduction in 70 pressure within and beyond the T fitting in a manner to lift the condensate through the distance approximating the radius of the roll 75.

In case the fitting 81 may not be utilized as an ejector, it will appear that there is normally re- 75

quired a greater pressure drop through and beyond the element 75, particularly in the line 85, than is necessary in connection with the pressures 55 which will tend to drain themselves of condensate largely by gravity. In order to provide the requisite differential in pressure drop, and to compensate for the normal difference in steam flow through the units such as 55 and 75, I have provided what may be termed a balancing loop, 10 structurally identified in the present example with the U shaped portion 61 of the return line 60. As will appear from Fig. 4, this will provide a water seal and a definite pressure head tending to oppose the delivery of condensate from the 15 lines 58 and 60 to the receiver 62. This arrangement has been found in practice to maintain a self-perpetuating column of condensate 90 in the U shaped leg or loop 61, which is substantially that desired to compensate for the pressure drop 20 in line 85 necessary to lift the condensate from the bottom portions of the rolls, into the return line 85.

Since the function of the several items of apparatus has been described in connection with 25 the structure of each, the operation of the system as a whole is now thought to be obvious to those skilled in the art, it being noted that the steam generated by the boiler is delivered via the supply lines to the consuming units, whence 30 the condensate is delivered by the return lines to the receiver, wherein the flash steam is condensed, and condensate together with makeup water is returned to the boiler by the centrifugal pump. The pump and other major items are 35 connected in a closed, air-free system and fully attain each of the objects herein expressed and implied.

I claim as my invention:

1. In a steam-producing and consuming system, a boiler, a plurality of steam-consuming units of dissimilar steam consuming and condensate-forming characteristics, supply piping connecting the boiler and said units, return piping connecting the units to the boiler, the return piping including a condensate reservoir, a centrifugal pump of open impeller type, having its intake connected to the lower portion of the reservoir and completing the return line therefrom to the boiler, the pump being of continuously-operating type and adapted to separate steam and condensate water, the return line from at least one of the steam-consuming units to the reservoir being characterized by a portion extending to a point substantially below the zone 55 of connection of the pump to said reservoir, and so arranged as normally to maintain in said portion of the return line, a body of condensate tending to oppose, by a predetermined hydrostatic head, the flow of condensate from the consuming 60 unit to which it is connected.

2. In a steam-producing and consuming system, a boiler, a plurality of steam-consuming units of dissimilar steam consuming and condensate-forming characteristics, supply piping connecting the boiler and said units, return piping including a condensate reservoir, a centrifugal pump of open impeller type, a connection from the lower portion of the reservoir to the pump, and completing the return line to the boiler, the pump being of a continuously-operating type and adapted to separate steam and condensate water, the return line from at least one

of the steam-consuming units to the reservoir being characterized by a portion extending to a point substantially below the zone of connection of the pump to said reservoir and so arranged as normally to maintain in said portion of the 5 return line, a body of condensate tending to oppose, by a predetermined hydrostatic head, the flow of condensate from the consuming unit to which it is connected, the several portions of the return piping between the consuming units and the condensate reservoir, as well as said reservoir, pump and return piping to the boiler, being characterized by absence of check valves, and arranged to provide a continuously open return system from the consuming units through the 10 reservoir and pump, to the boiler.

3. In a steam-producing and consuming system, a boiler, a pair of steam-consuming units of dissimilar steam consuming and condensate-forming characteristics, supply piping connecting 20 the boiler and said units, return piping connecting the units to the boiler, the return piping including a condensate reservoir, separate return lines from the consuming units to the reservoir, a centrifugal pump of open impeller type, having 25 its intake connected to the lower portion of the reservoir and completing the return therefrom to the boiler, the pump being of continuously-operating type and adapted to separate steam and condensate water, the return line from one 30 of the steam-consuming units to the reservoir including a U-shaped, balancing loop portion extending from the associated unit to a point substantially below the zone of connection of the pump to said reservoir, the last said return 35 line being characterized by absence of obstructions, and so arranged as normally to maintain in said portion of the return line, a body of condensate tending to oppose, by a predetermined hydrostatic head, the flow of condensate from 40 the consuming unit to which it is connected.

4. In a steam-producing and consuming system, a boiler, a plurality of steam-consuming units of dissimilar steam consuming and condensate-forming characteristics, supply piping 45 connecting the boiler and said units, return piping connecting the units to the boiler, the return piping including a condensate reservoir, means for automatically relieving the reservoir of air collecting therein, a centrifugal pump of open 50 impeller type, a connection from the lower portion of the reservoir to the pump, and completing the return line to the boiler, the pump being of a continuously-operating type and adapted to separate steam and condensate water, means as- 55 sociated with the pump for adjusting its impeller clearance, the return line from at least one of the steam-consuming units to the reservoir being characterized by a wide, U-shaped portion extending to a point substantially below the zone 60 of connection of the pump to said reservoir and constituting a balancing loop so arranged as normally to maintain in said portion of the return line, a body of condensate tending to oppose, by a predetermined hydrostatic head, the flow of 65 condensate from the consuming unit to which it is connected, the several portions of the condensate return piping between the consuming units and the condensate reservoir, as well as said reservoir, being arranged to provide a continuously 70 open return system from the consuming units through the reservoir and pump, to the boiler.

MINOR W. STOUT.
